DESIGN FOR A BRUSH KNIFE

Richard D. Brown, Olean, N. Y.

Application February 16, 1942, Serial No. 105,837

Term of patent 14 years

To all whom it may concern:

Be it known that I, Richard D. Brown, a citizen of the United States of America, residing at Olean, in the county of Cattaraugus and State of New York, have invented a new, original, and ornamental Design for a Brush Knife, of which the following is a specification, reference being had to the accompanying drawing, forming a part hereof.

In the drawing:

I claim:

The ornamental design for a brush knife, as shown.

RICHARD D. BROWN.
